UNITED STATES PATENT OFFICE.

CHARLES M. HALL, OF BROOKLYN, NEW YORK, ASSIGNOR OF TWO-THIRDS
TO WILLIAM WALTON AND JACOB FAESSLER, BOTH OF SAME PLACE.

DESIGN FOR A MEMORIAL PLAQUE.

SPECIFICATION forming part of Design No. 16,768, dated July 6, 1886.

Application filed March 8, 1886. Serial No. 194,503. Term of patent 7 years.

To all whom it may concern:

- Be it known that I, CHARLES M. HALL, a citizen of the United States, residing at Brooklyn, in the county of Kings and State of New York, have invented and produced a new and original Design for a Veteran's Memorial Plaque, of which the following is a specification, reference being had to the accompanying drawing, forming part thereof.
- My record plaque consists of a circular disk flat or slightly concave or convex, having at its center a representation of the badge of the Grand Army of the Republic. Surrounding the outer edge of the disk are a series of blank spaces, some round and others oblong, and either depressed below or raised above the general surface. At the top of the plaque, between the central design and the outer row of spaces, is a representation of the coat of arms of the United States. At various points in this inner belt of the disk are conventional representations of the surrender of General Lee, Fort Sumter, a drum-stack, a stack of muskets, a cannon and pile of shot, and, finally, a soldier and sailor supporting a blank shield, the whole being arranged substantially as shown.
- A, &c., are blank spaces following the outer curve of the disk. C is a larger space of the same shape.
- D are small blank circular spaces; B, a blank shield of oval shape, supported upon either side by a soldier, M, and a sailor, N.
- F is the badge of the Grand Army of the Republic. 35
G is a representation of Fort Sumter.
H is a conventional representation of the surrender of General Lee.
I is a conventional representation of a drum-stack. 40
K is a conventional representation of a stack of muskets.
L is a conventional representation of a cannon and pile of shot.
Having now fully described my invention, 45 what I claim, and desire to secure by Letters Patent, is--
- A memorial plaque consisting of a disk having around its outer edge a row of oblong blank spaces with round blank spaces, at its center the shield of the Grand Army of the Republic, above this central design the coat of arms of the United States, and at various other parts of its surface conventional representations of the surrender of Lee, a stack of 50 muskets, a drum-stack, Fort Sumter, a cannon and pile of shot, and a soldier and sailor supporting a blank shield, all arranged substantially as shown and described.

CHARLES M. HALL.
